PUNCHBOARD GAME APPARATUS

Herman L. Smith, Grifton, N. C.

Application November 17, 1936, Serial No. 111,320

7 Claims. (Cl. 312—49)

This invention relates to amusement devices and particularly to what are known as punch boards in which a board having a large number of holes is used, the player or user forcing a pin into 5 any selected hole in the board and thereby securing the delivery of certain articles or securing a prize.

One of the objects of this invention is to provide a device of this kind which is very simple, 10 which may be cheaply made, which is not liable to get out of order, and which is entirely legal, because an article is delivered each time the board is punched.

Other objects will appear in the course of the 15 following description.

My invention is illustrated in the accompanying drawings wherein:

Figure 1 is a perspective view of my game apparatus.

20 Figure 2 is a vertical sectional view through the machine but showing a pin inserted through the pin board and forcing one of the balls out from its seat.

Figure 3 is a fragmentary section on the line 25 3—3 of Figure 2.

Figure 4 is a vertical fragmentary section on the line 4—4 of Figure 3.

Figure 5 is a fragmentary top plan view of the cross piece 13.

30 Figure 6 is a section on the line 6—6 of Figure 5.

Figure 7 is a fragmentary section through the casing showing the flutes or spiral grooves on the roller.

35 Figure 8 is a horizontal section on the line 8—8 of Figure 9.

Figure 9 is a vertical section on the line 9—9 of Figure 8, these two figures showing a modified form of ball holding guideway.

40 It will be seen from Figures 1 and 2 that my game apparatus comprises an outer casing designated generally 10, which may be made of metal, wood or any other suitable material, and which is provided with a back, a hinged top 11, a front

45 board 12 extending downward from the top, and a transversely extending member 13 which is spaced from the lower edge of the board 12 to leave an aperture 14 through which the articles delivered may be seen. The member or portion 13 has

50 below it an area 15 which is formed with a plurality of vertical rows of holes 16. For instance, there may be ten rows of holes and ten holes to each row, thus giving a hundred apertures, any one of which may be selected for punching.

55 Below the apertured punch board 15 there is a

window 17 which discloses the number of balls punched when the player is through punching. Below the window there is an opening 18, and below this opening there is a downwardly and forwardly inclined floor 19. The forward end of 5 this floor extends out beyond the member 18 and constitutes a tray within which the article punched out is received.

The upper portion of the casing 10 between the front 12 and the back and below the top is formed 10 to provide a magazine 20 for the goods being delivered. These articles or goods will preferably be in the form of balls of chewing gum or marble balls or candy balls, or anything of this nature. These objects will be preferably spherical in form. 15

Just below the window or display opening 14, there is disposed an upwardly and inwardly inclined shelf 21 which will catch and hold a number of the articles being vended, so that these may be displayed through the window 14 and the 20 player can see the article he is to get.

The transverse bar 13, as illustrated, has a downward extension which constitutes the punch board 15. The portion 13 is relatively thick and the upper face is downwardly and inwardly inclined at 22, and opposite this is a downwardly and inwardly inclined shelf 23. Disposed between the inner face of the member 13 and this shelf 23 and on a level with the downwardly extending ends of the face 22 and of the shelf 23, 25 is a roller 24 pivotally mounted in the end walls of the casing and which has a detailed construction, 30 as will be later described.

As before stated, the cross bar 13 is integral with the punch board 15, but this cross bar 13 35 projects inward beyond the inner face of the board 15 and is formed, as shown in Figures 5 and 6, with a plurality of vertical semi-circular guide recesses 25. The roller 24 quite closely approximates the edges of the walls of these recesses, 40 but is spaced sufficiently therefrom to permit any one of the balls A to pass between the roller 24 and into any one of the guide recesses 25. This roller, when rotated, acts to stir the balls A up within the magazine 20 and thus mix these balls 45 up. The roller is adapted to be rotated by means of a key 26 adapted to be inserted through a key hole in one end wall of the casing. Preferably the roller is spirally grooved about three-fourths of its circumference, as at 27, so as to secure a 50 lateral movement for the balls A, as well as a feeding movement. A clockwise rotation of the roller 24 will tend to carry the balls downward into the guides 25. A counter-clockwise rotation, however, will dislodge balls which may by chance 55

have become jammed in the throat formed by the roller 24 and the walls of the recess 25. A portion of the roller may be left entirely free of these spiral grooves 27 in order that pressure 5 against the walls of the metal tubes 28 may be relieved.

Disposed against the inner face of the board 15 are a series of vertical tubes or guides designated 28. Each of these guides or nearly circular tubes 10 is made of metal, and each tube is formed to leave a vertically extending open space 29. In other words, each guide 28 has the form in cross section of somewhat more than a semi-circle. Each tube 15 20 is formed with a plurality of circumferentially extending slits 30 extending inward from the opposed edges 31 of the tube, these slits extending partly into the tube so that wings 33 are provided which are somewhat elastic. That portion of each tube which faces against or confronts the inner 25 face of the punch board 15 is provided with a plurality of apertures 34 which correspond in number to a vertical series of apertures 16 in the punch board, and thus an implement such as the implement 35, may be inserted through the perforations 16 and through the perforations 34 to force any article which is opposite one of these 30 perforations 34 out between the resilient wings 33. When the article is forced out between these wings, it will drop downward onto a trap 36. This 35 trap 36 is pivoted intermediate its ends and is disposed in a plane adjacent the plane of the opening 17. The forward edge of this trap or false floor 36 is held in position just opposite the lower edge of the opening 17 by means of a coiled contractile spring 31. The rear end of the trap 36 is connected by a connecting rod 38 or other suitable means to the end of the roller 24 or to a disk carried by this roller, the roller having a pin 39, with which the end of the link 38 loosely 40 engages. It will be obvious now that when the roller is turned in either direction from what may be termed its normal position, the rear end of the trap door will be elevated and all the articles gathered upon this trap will be dropped onto the tray 19 and will roll downward and be discharged to the opening 18.

It will be noted that the punch board 15 is relatively thick. In actual practice, it will be about 1½ in. thick and the holes 16 will be relatively small so as to prevent a player seeing through these openings and thus seeing the color of the balls which are disposed behind these openings.

In the operation of this device, it will be seen 55 that whenever the pin 35 is inserted through the selected aperture 16, a ball of chewing gum, candy, a marble or other like article will be forced out from between the wings with which the ball happens to be coincident, and that because of the downward and forward inclination of the punching board and of the ball tubes 28, the articles so punched out will drop upon the trap door 36. Every time that a ball is punched out 60 from any of the sections of any tube, a ball from the ball compartment or magazine will drop down into place in the top of the ball tube 28, and obviously when a ball is pushed out from one of the lower sections of the tube 28, the balls from above will drop down, and a ball from the magazine will roll into the top of the tube. Thus these 65 tubes get continually filled.

One of the important features of this invention lies in the fact that it is of relatively small and convenient size, and this is secured by providing 70 a magazine from which the balls are constantly

discharged into the ball guides or tubes, so that the dimensions of the actual punch board may be relatively small, and it is not necessary for the punching board 15 to have more than 100 or 150 balls behind it. Obviously the size of the ball 5 used will determine the number of holes which may be placed in the punching section or board 15 and this, of course, will determine the height of the several winged sections of the arcuate tube 28. When the player is through playing, the merchant will rotate the roller 24 in a direction to stir up the balls and mix them up, the spiral grooves 27 acting to shift the balls toward the middle of the machine and thus mix them up all the more. 10

When the selected numbers have been punched by a player, the balls or other articles so punched out will drop upon the trap door 36 and then the merchant can rotate the roller 24 by means of a key and discharge the balls that have 20 gathered upon the trap door upon the tray 19 and these may be withdrawn. Inasmuch as these balls are of chewing gum, candy or of like articles, it is obvious that there is always an article vended to the purchaser and player. The balls 25 may have numbers on them or may be differently colored and certain numbers or colors will secure premiums from the merchant. 15

While preferably I use the resilient metallic tubular members 29, I do not wish to be limited 30 to the construction of these members of metal, and in Figures 8 and 9, I have shown a member 28^a formed of relatively soft rubber which provides a series of vertical guideways, each nearly circular in plan view, and which is so constructed 35 as to provide the wings 33^a of relatively soft but resilient rubber past which the balls or other devices A may be forced. Each partially tubular guideway has its wings 33^a transversely slotted, as at 30^a, for the same purpose as in the construction shown in Figures 2 and 3. 40

The roller 24 is preferably, in actual practice, about 2½ inches in diameter and the grooves 27 about ¼ of an inch wide and about ⅛ of an inch deep. The purpose of the roller is to stir the 45 balls in the magazine every time the merchant with his key releases the trap 36. When the roller is turned in a clockwise direction in Figure 2, it throws the balls forward and down into the guide grooves 25, then down into the tubes 28. 50 When the tubes 28 and 25 are full, the top balls will be likely to catch in the grooves of the roller and cause pressure on the metal tubes 28 if the roller were grooved all the way around so that portion of the roller which is normally on top, 55 as shown in Figure 2, is left ungrooved to prevent this pressure when the roller is turned to the right.

It is to be noted in Figure 2 that the trap 36 is so disposed that the punched out balls or other 60 articles rest on the trap 36 adjacent the window 17, and when the trap door is shifted to the position shown in dotted lines in Figure 2, the free edge of the door does not come in view through the opening 18. The opening 18 is only slightly 65 larger than the article being vended and by having the free end 36 stop at a point above the upper edge of the opening 18, it makes it difficult for someone to cheat the machine by holding the trap door down with the fingers or with an instrument and then punching out the balls. 70

Of course, it will be understood that when a ball is punched out of a column, all the balls above the punched out ball fall down one step and other balls in the magazine immediately fall 75

5 into the guide grooves 25 until the column is filled up again. Sometimes, the balls will not immediately enter the guide grooves 25 and then the partially grooved roller stirs up the balls in the 10 magazine causing those which happen not to enter the guide grooves 25 to enter when the roller is turned.

10 It is obvious that the recesses 25 together with the nearly circular tubular members 28 below these recesses constitute vertical guideways down which the balls from the magazine travel and that these guideways are divided to provide a plurality of pairs of resilient wings normally embracing the balls but adapted to be forced 15 apart when a ball is forced out, as shown in Figure 2.

20 While I have illustrated certain details of construction and arrangement of parts, I do not wish to be limited thereto as obviously many minor changes might be made without departing from the spirit of the invention as defined in the appended claims.

What is claimed is:—

25 1. In a game of the character described, an element having a vertical row of perforations, a semi-tubular guideway extending vertically behind the element and aligned with the row of perforations and formed to provide a vertical series of pairs of inwardly curved resilient wings, 30 the guideway being adapted to receive a series of globular objects having a diameter approximately equal to the cross section of the guideway and approximately equal to the vertical length of each pair of wings, the vertical row of perforations in the element opening into the guideway each before the middle of a pair of wings.

40 2. In a game apparatus of the character described, a casing, the face of the casing below the upper portion thereof having a plurality of vertical rows of perforations, a plurality of vertical guideways on the inside of the perforated portion of the casing, each guideway being obstructed at its lower end, each guideway having a plurality of pairs of resilient wings, each pair 45 being slightly spaced from the next adjacent pair by a slot in said guideway, the perforations opening into these guideways opposite the middle of each pair of wings whereby an instrument may be inserted through the perforation to force out an object immediately behind the perforation.

50 3. In a game apparatus of the character described, including a casing, the front of the casing below the upper portion thereof being formed to provide a punch board having a plurality of vertical rows of perforations, a plurality of vertical guideways on the inside of the punch board, each guideway being obstructed at its lower end and each guideway being formed to provide a plurality of pairs of resilient wings, each pair of 55 wings being separated from the next adjacent pair by a slot in said guideway, the perforations through the punch board opening into these guideways opposite the middle portion of each pair of wings, the casing above said punch board constituting a magazine for the articles to be 60 dispensed, and means at the lower end of the magazine for guiding the articles into said guideways.

70 4. In a game apparatus of the character described, including a casing, the front of the casing below the upper portion thereof being formed to provide a punch board having a plurality of vertical rows of perforations, a plurality of vertical guideways on the inside of the punch board, each 75 guideway being obstructed at its lower end and

each guideway being formed to provide a plurality of pairs of resilient wings, each pair of wings being separated from the next adjacent pair by a slot in said guideway, the perforations through the punch board opening into these guideways opposite the middle portion of each pair of wings, the casing above said punch board constituting a magazine for the articles to be dispensed, and a roller mounted at the upper ends of the guideways and closely adjacent thereto and acting to guide objects in said magazine into said guideways.

5 5. In a game apparatus of the character described, including a casing, the front of the casing below the upper portion thereof being formed to provide a punch board having a plurality of vertical rows of perforations, a plurality of vertical guideways on the inside of the punch board, each guideway being obstructed at its lower end and each guideway being formed to provide a plurality of pairs of resilient wings, each pair of wings being separated from the next adjacent pair by a slot in said guideway, the perforations through the punch board opening into these guideways opposite the middle portion of each pair of wings, the casing above said punch board constituting a magazine for the articles to be dispensed, a roller mounted at the upper ends of the guideways and closely adjacent thereto and acting to guide objects in said magazine into said guideways, said roller having spiral grooves on its face, the grooves extending only partially around the roller, and means on the exterior of the casing whereby the roller may be rotated to thereby agitate the objects in the magazine.

10 6. In a game of the character described, a casing, the face of the casing below the upper portion thereof being formed to provide a punch board having a plurality of vertical rows of perforations, a plurality of vertical guideways on the inside of the punch board, each guideway being obstructed at its lower end and each guideway being formed to provide a plurality of inwardly curved resilient wings, each pair of wings being separated from the next adjacent pair by a slot in said guideway, the perforations through the punch board opening into said guideways in the middle plane of said wings, a roller mounted within the casing immediately opposite the upper ends of said guideways and closely adjacent thereto, the roller acting to guide objects within said magazine into said guideways, a trap pivotally mounted below the guideways and onto which objects discharged from said guideways may be collected, means urging the trap into an approximately horizontal position, and means connected to the roller whereby when the roller is rotated, the forward end of the trap will be depressed to discharge the objects collected thereon.

15 7. In a game apparatus of the character described, a casing, a pin board forming part of the lower portion of said casing, the pin board being relatively thick, the upper end of the pin board being downwardly and inwardly inclined, 20 downwardly extending guide recesses formed in the inner face of the upper portion of the pin board, the recesses being semi-circular in cross section, that portion of the pin board below said recesses being formed with a plurality of vertical rows of perforations extending from the exterior of the pin board to the interior face thereof, the inner face of the pin board immediately below the recesses having attached thereto a series of vertical semi-tubular members extending down

to the lower end of the pin board, each of said members at its lower end being obstructed, said members being transversely slitted at intervals to provide a plurality of pairs of inwardly curved 5 resilient wings, each perforation in the pin board opening through to the inner face of said member immediately opposite the middle plane of a pair of wings, means for guiding objects in the

magazine into said guide recesses and thence into the upper ends of said semi-tubular members, said means also constituting agitating means, a trap upon which the objects dislodged from between said wings may gather, and means for 5 opening said trap to discharge the objects.

HERMAN L. SMITH.
